UNITED STATES PATENT OFFICE.

JOLLIFFE WALKER, OF MONTREAL, QUEBEC, CANADA.

DESIGN FOR A STATUETTE.

41,361.

Specification for Design.

Patented May 9, 1911.

Application filed February 9, 1911. Serial No. 607,703. Term of patent 7 years.

To all whom it may concern:

Be it known that I, JOLLIFFE WALKER, a subject of the King of Great Britain, residing at Montreal, in the county of Hochelaga, Province of Quebec, Canada, have invented a new, useful, and ornamental Design for Statuettes, of which the following is a specification.

Reference is had to the accompanying drawing, in which the figure of the drawing is a perspective view of a statuette, showing my new and ornamental design.

I claim:

The ornamental design for a statuette, as shown.

In testimony whereof I affix my signature in presence of two witnesses.

JOLLIFFE WALKER.
